[57] ABSTRACT

An apparatus for ejecting coke from a coking furnace includes a coke box which is mounted on a car for transverse movement toward and away from the furnace doors and for longitudinal movement on a carriage along the length of the coking furnace battery. The coke box is shorter than the coke cake to be received and it includes a movable coke cake guide arranged between the chamber door frame and a coke box. The coke cake guide is movable along a platform alongside the furnace doors between the furnace doors and the coke box.

APPARATUS FOR EJECTING COKE FROM A COKING FURNACE

BACKGROUND OF THE INVENTION

1. Field of the Invention

This invention relates in general to coking furnace apparatus and in particular, to a new and useful device for transferring coke cake from a furnace through a guide and then into a coke box.

2. Description of the Prior Art

German Pat. application P 18 12 383.6 corresponding to U.S. Pat. application Ser. No. 880,976 concerns an arrangement for the emission-free ejection, reception, evacuation and wet-quenching in a quenching tower of glowing coke which is ejected from horizontal coking furnaces. The patent application discloses a coke box which moves on a track in front of the coking furnace chambers. This box has substantially the dimension of the coke cake to be received. The box is provided with a bottom flap oriented to open into a coke bin arranged in the range of the track and which includes a closable upper opening. The system includes a coke chimney flue arranged under the coke bin, and a coke quenching chamber with a chimney connected to the flue. German Pat. application P 1928 866.5 corresponding to U.S. Pat. application Ser. No. 880,976 concerns the arrangement of a coke receiving pocket underneath the coke box, and the coke box is made shorter than the coke cake to be received.

The present invention relates to an improvement of a construction in which the coke box is made shorter than the coke cake to be received. This has the advantage that it can be subsequently installed in existing plants because of the small space required. It needs no separate coke feed but it also has the disadvantage that the door lifting, the door, and the door frame cleaning cart cannot pass by the coke box on the platform formed on the roof of the master gangway. This cart must always and constantly be on one side of the coke box on which it is arranged. A second such cart is therefore required for operating the furnace chamber arranged on the remote side at the end of the battery.

A door lifting device which can be moved completely independently of the coke box in front of the battery and with which the cleaning devices for the doors and the door frames can be combined, would therefore represent a technical progress.

In the arrangement according to the invention in which the coke box length is shorter than that of the coke cake to be received, there is a movable coke cake guide arranged between the furnace chamber, door frame and coke cake, which can pass freely between the battery and the coke cake. In this design, the door lifting device on whose under-carriage can also be arranged the cleaning devices can now also pass in both directions past the coke box. This means that only one door lifting device and only one cleaning device is necessary to operate the entire battery.

SUMMARY OF THE INVENTION

In accordance with the invention the coke cake guide, the door lifting device and the door and door frame cleaning device are carried on a common under-carriage which moves along the coke furnace battery. The apparatus also includes gas exhaust and gas cleaning devices arranged on the upper part of the coke box at a level which corresponds to the gas collecting cham-

ber of the furnace chamber. This ensures that there will be no gas-dust emissions when the coke is transferred from the furnace chamber into the coke receiving pocket. Care has been taken that no dust discharges into the atmosphere between the chamber door frame and the coke guide applied thereto. A suction pipe is arranged in the upper region of the coke box and it is connected to a duct in the upper region of the coke cake guide when the coke box is attached in front of the coke cake guide. The pipe has, at its end, wide openings which permit the exhaust of dust from the chambers formed by door frames, tie rod stands, coke cake guide and packing plates arranged thereon. The exhaust devices can be operated with fans or other exhausting means, for example, steam exhaust turbines which may also be equipped with wet separators or cyclone separators. In a preferred arrangement the coke box comprises a cast iron plate construction suspended loosely in a steel frame. Several coke cake guide cars are arranged on a coking furnace battery which are alternately connected to the coke box and to the coke receiving pocket if desired.

Accordingly, it is an object of the invention to provide a coking furnace construction which includes a coke box for receiving the glowing coke cake which is shorter than the coke cake to be received and which includes a movable coke cake guide arranged between the chamber door frame and the coke box which can pass freely along the coke furnace battery.

A further object of the invention is to provide a coking furnace apparatus which includes an undercarriage movable along the trackway in front of a coking furnace battery along the length thereof and a coke box carried on a car which is movable transversely on the carriage toward and away from the furnace doors and which also includes a coke cake guide which is movable on a ramp defined alongside the furnace doors at a location between the doors and the coke box.

A further object of the invention is to provide a coking furnace system which is simple in design, rugged in construction and economical to manufacture.

The various features of novelty which characterize the invention are pointed out with particularity in the claims annexed to and forming a part of this disclosure. For a better understanding of the invention, its operating advantages and specific objects attained by its uses, reference should be had to the accompanying drawing and descriptive matter in which there is illustrated and described a preferred embodiment of the invention.

BRIEF DESCRIPTION OF THE DRAWING

In the drawing:

FIG. 1 is a partial side elevational view of a coking furnace battery having a coke discharge system constructed in accordance with the invention;

FIG. 2 is a front elevational view of the discharging device shown in FIG. 1;

FIG. 3 is a partial top plan view of the furnace shown in FIG. 1; and

FIG. 4 is an enlarged partial plan of a portion of the apparatus adjacent the furnace shown in FIG. 3.

GENERAL DESCRIPTION OF THE PREFERRED EMBODIMENT

Referring to the drawings in particular, the invention embodied therein comprises a coking furnace battery which includes a plurality of horizontal coking fur-

naces arranged in a row. The battery has a roof 2 and tie rod stands 3 at the furnace door end.

In accordance with the invention, the front of the furnace is provided with a ramp 4 over which is movable a guide car 122 which contains a coke cake guide 99 which moves along the ramp 4 on the rails 123.

Tracks or rails 7 extend along the length of the furnace and an undercarriage or support structure moves along the tracks on wheels 10. A coke box 11b is provided with a wheeled carriage 9 which backwardly and forwardly on a support beam 13 of the undercarriage 8 and in directions toward and away from the furnace doors at the location of the tie rod stands 3.

The glowing coke cake which is moved from each furnace chamber is pressed from the chamber through the coke cake guide 99 which is applied tightly to the furnace chamber to be emptied. The coke cake is moved in the glowing condition through the guide and into the coke box 11b. The coke box 11b is then moved backward a little and both the furnace chamber and the end face of the coke box 11b are closed with doors (not shown).

During the evacuation of the furnace chambers the dust vapors are withdrawn by steam exhausters 103 and 115 through lines 106 and 111 from the upper collecting chambers of the coke cake guide 99 and of the coke box 11b as shown particularly in FIG. 2. The withdrawn vapors are delivered through lines 104 and 114 into cyclone separators 105 and 113.

Because the coke cake guide 99 cannot be attached very tightly on the door frame 117, some dust escapes into chamber 121 during the ejection of the coke cake as shown in FIG. 4. This chamber is formed between the door frame 117, the walls of the coke cake guide 99 and the tie rod stands 3 together with the carriers 122 which are attached on the walls 118 and the packing plates 119 which are secured on the carriers 122.

The withdrawn gasses are delivered through the slots 120 of the walls 118 into duct 98 which is arranged at the top of the coke cake guide 99 and into the line 100 which is arranged at the top of the coke cake box 11b. This duct 100 is connected to the duct 98 when the coke box 11b is attached in front of the coke cake guide 99. The withdrawn gases are moved into a separator 109. The vapors and the gases liberated of the dust are released into the atmosphere through the chimneys 105a, 108 and 112. The separated dust is withdrawn from the lower part of the separators 105, 109, and 113. When the flowing coke is transferred to a receiving bin any dust emissions are prevented by a telescopic hood 116 which may be moved downwardly to enclose over the device receiving the coke.

The coke box 11b and the coke quenching cars are made of a steel frame construction with loosely sus-

pended cast iron plates which can expand freely on heating and which are freely accessible as bin walls to the cooling outside air.

While a specific embodiment of the invention has been shown and described in detail to illustrate the application of the principles of the invention, it will be understood that the invention may be embodied otherwise without departing from such principles.

We claim:

- 10 1. An apparatus for use in the discharge of glowing coke cake from a coke furnace having a plurality of furnace chambers arranged in a horizontal row, comprising an enclosed coke box for receiving the coke cake, carriage means supporting said coke box for movement alongside as well as transversely towards and away from said furnace for presentation of said coke box in alignment with each furnace chamber in succession for receiving the coke therefrom, an enclosed coke cake guide movable between the furnace chambers and said coke box and defining a guide passage between said furnace chambers and said box for the passage of the glowing coke cake therethrough, gas exhauster means carried by said coke box adapted to extend into the upper part of each furnace chamber for removing the gases therefrom during the discharge of the coke, said gas exhauster means including an exhauster conduit carried by said coke box and extending outwardly therefrom for exhausting the furnace cases, a connecting exhaust conduit carried by said coke cake guide and alignable with said exhauster conduit and having suction means engageable into the top of said furnace for removing the gases from the furnace through the conduit in said guide and through said exhaust conduit in said coke box, said coke cake guide including an end adjacent the furnace chambers having a slot therein, a furnace tie rod stand at the front of each furnace chamber, guide means between said tie rod stand and said coke cake guide defining a chamber 121 around the entrance to the furnace chamber which communicates with said slot, said exhauster means also including an exhauster duct connected to said chamber for exhausting the gases which may accumulate in said chamber during the discharge of the coke cake.
- 15 2. An apparatus, according to claim 1, including means on said guide car for cleaning the door and the door frame of each furnace chamber.
- 20 3. Apparatus, according to claim 1, wherein said exhauster means includes means for separating the dust from the gases.
- 25 4. Apparatus, according to claim 1, wherein said coke box comprises a housing with cast iron plates, and a surrounding frame loosely suspending said plates within said frame.
